CEILING MOUNTED FLUORESCENT LIGHT FIXTURE

Ernest Monte, Pasadena, Calif., assignor to Sunbeam
Lighting Co., Los Angeles, Calif.

Filed July 21, 1971, Ser. No. 164,982

Term of patent 14 years

Int. Cl. D26—05

U.S. Cl. D48—23 A

FIG. 1

FIG. 2

FIG. 3

FIG. 1 is a side elevational view of a ceiling mounted fluorescent fixture showing a new design;

FIG. 2 is a front elevational view thereof;

FIG. 3 is a bottom plan view thereof; and

FIG. 4 is a perspective view thereof.

I claim:

An ornamental design for a ceiling mounted fluorescent light fixture, as shown and described.
